UNITED STATES PATENT OFFICE

CARLO DE FILIPPI, OF MILAN, ITALY

ELECTRIC-PNEUMATIC THERMOSCOPE AVAILABLE AS FIRE INDICATORS AND FOR
LIKE PURPOSES

Application filed May 17, 1929, Serial No. 363,981, and in Italy April 10, 1929.

The present invention relates to a new kind of electric-pneumatic thermoscope, which is of a very sensitive operation, simple in construction and may be easily assembled and disassembled, the same being particularly available as a fire indicator and for like purposes.

The thermoscope forming the subject of the present invention is mainly formed by a curved tube containing a certain amount of mercury and prolonged at its ends by two diverging tubular branches ending in two spherical bulbs or the like, filled with air or other suitable gases.

One of the bulbs is completely protected against surrounding heat, while the other is readily affected by the heat, so as to cause, when the external temperature rises, a dilatation of the gases it contains, which dilating themselves through the corresponding tubular branch cause a displacement of the mercury contained in the lower curved tubular body. The displacement of the mercury closes an electric circuit of an optic or acoustic indicator, the conductors of which are connected with two contacts placed inside the tube.

The main characteristic of the improved thermoscope consists in the fact that said tubular body is placed in a casing formed from complementary half boxes which are clamped together by means of screws and which are provided at their heads with two diverging members for receiving the bulbs, one of these members having a side wall, while the other has slots therein, which coincides with the slots of the other member when assembled to permit the circulation of air. A tubular body is supported within the casing by straps, or other suitable means.

The spirit of the invention will be easily understood with reference to the annexed drawings, showing by way of an example one of the possible embodiments of the thermoscope forming the subject of the present invention.

In the said drawings:

Fig. 1 is a front view of the thermoscope with one of the half boxes of the casing removed.

Fig. 2 is a cross section through the thermoscope.

Fig. 3 is a plan view of the same.

Fig. 4 is an external front view of it.

According to the drawings, —1— is the curved tube containing the mercury —2— and prolonged by the tubular branches —3— and —4— which end respectively in bulbs —5— and —6— filled with air or other gases; —7— and —8— are the two half boxes forming the casing for the tubular body and connected with one another by means of screws —9— and —10— and provided respectively the one with the prolonged parts —7'—, —7"— and the other with the prolonged parts —8'—, —8"—, so disposed as to suitably contain when the device is assembled, in the box like body formed by —7— and —8— the bulb —5— and in the box like body formed by —7"— and —8"— the bulb —6—; —11— and —12— are slots formed in the wall of the parts —7— and —8— respectively, to permit free access of air to the bulb —5—; —13— and —14— are terminals adapted to be connected with an electric device for optic or acoustic signals; —15— and —16— are the contacts for the conductors —17— and —18— when connected with the terminals —13— and —14—; —19— are straps serving to hold the tubular body in place; —20— is a washer carrying the straps by which said body is supported; and —21— is an opening of the front wall of the part —7"—.

It is obvious that details of construction and form of the apparatus above described may be varied without departing from the spirit of the present invention.

Having now particularly described and ascertained the nature of my said invention and the manner in which the same is to be performed, I declare that what I claim is:

A device of the class described comprising a casing consisting of complementary sections, each section having divergently disposed prolongations having box terminals, means carried by the sections to retain the same in detachably clamped relationship, a washer carried by one of the sections and having straps carried thereby for disposi-

tion within the casing, a tube having a looped portion, the arms of which terminate in divergently disposed branches having bulbs upon their ends for engagement in the respective boxes, said straps engaging the branches of the tube to maintain the same centralized in the casing, said loop having contacts associated therewith, mercury in the loop cooperating with the contacts, said bulbs having gas therein for displacing the mercury to close the contact when the bulbs are subjected to abnormal heat, one of said boxes being closed and the other having openings therein, as and for the purpose set forth.

10   mercury to close the contact when the bulbs are subjected to abnormal heat, one of said boxes being closed and the other having openings therein, as and for the purpose set forth.

15   In testimony whereof I affix my signature.

CARLO DE FILIPPI.
